US00D889770S

(12) **United States Design Patent** (10) **Patent No.:** **US D889,770 S**
(45) **Date of Patent:** **** Jul. 14, 2020**

(54) **T-SHIRT**

(71) Applicant: **Refried Tees, Inc.**, South Dartmouth, MA (US)

(72) Inventor: **Lisa Litos**, South Dartmouth, MA (US)

(73) Assignee: **Refried Tees, Inc.**, South Dartmouth, MA (US)

(**) Term: **15 Years**

(21) Appl. No.: **29/686,963**

(22) Filed: **Apr. 9, 2019**

Related U.S. Application Data

(62) Division of application No. 29/591,139, filed on Jan. 17, 2017, now Pat. No. Des. 848,119.

(57) **CLAIM**

The ornamental design for a T-Shirt, as shown and described.

DESCRIPTION

FIG. 1 is a perspective view of a T-Shirt showing my new design;

FIG. 2 is a front view thereof;

FIG. 3 is an enlarged view of the portion of the T-Shirt depicted in the detail circle of FIG. 2;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of a second embodiment of a T-Shirt showing my new design;

FIG. 10 is a front view thereof;

FIG. 11 is an enlarged view of the portion of the T-Shirt depicted in the detail circle of FIG. 10;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines shown in the drawings are for the purpose of illustrating stitching and form no part of the claimed design.

The different types of stippling shown in the drawings represents shading and does not form part of the claimed design.

1 Claim, 12 Drawing Sheets
